(57) **CLAIM**

The ornamental design for an ice sphere mold, as shown and described.

DESCRIPTION

FIG. 1 is a front perspective view of an ice sphere mold; FIG. 2 is a front elevation view thereof, the rear elevation view being an identical image thereof; FIG. 3 is a left side elevation view thereof, the right side elevation view being an identical image thereof; FIG. 4 is a top plan view thereof; and, FIG. 5 is a bottom plan view thereof.

The broken lines shown in the drawings depict portions of the ice sphere mold that form no part of the claimed invention.
